CLAIM

We claim the ornamental design for a light sensor, as shown and described.

DESCRIPTION

FIG. 1 is a front elevational view of a light sensor, showing our new design;

FIG. 2 is a rear elevational view of the light sensor of FIG. 1;

FIG. 3 is a left side elevational view of the light sensor of FIG. 1;

FIG. 4 is a right side elevational view of the light sensor of FIG. 1;

FIG. 5 is a top plan view of the light sensor of FIG. 1; and,

FIG. 6 is a bottom plan view of the light sensor of FIG. 1.

(Continued)

The broken lines illustrate environmental structure that forms no part of the claimed design.
